United States Patent Office.

HENRY SCHULTZ, OF CHICAGO, ILLINOIS.

Letters Patent No. 67,809, dated August 13, 1867.

IMPROVED SOFA AND BED.

The Schedule referred to in these Letters Patent and making part of the same.

TO ALL WHOM IT MAY CONCERN:

Be it known that I, HENRY SCHULTZ, of Prussia, now resident of Chicago, in the county of Cook, and State of Illinois, have invented new and useful Improvements in Sofa and Bed combined; and I do hereby declare that the following is a full and exact description thereof, reference being had to the accompanying drawings, making part of this specification, in which—

Figure 1 represents the longitudinal section of the frame.

Figure 2 the cross-section of the same, and

Figure 3 the tubular plate and rod.

The nature of my invention consists in arranging the seat of a sofa as an independent revolving frame, so that one side of it may be used as a sofa-cushion and the other side as a bed.

To enable others skilled in the art to make and use my invention, I will proceed to describe its construction and operation.

I construct the frame A of the seat separate from the balance of the frame, and mount it in the frame on journals B, placed one at the centre of each end, these journals fitting in notches or recesses C in the ends of the main frame, so that the seat may revolve on said journals, and thus be turned upside down. Its top is upholstered so as to be used as a sofa-cushion, while its bottom is flat and arranged in the shape of a bed. To the top cushion of the sofa is attached the back E, by means of metallic plates P P and screws, so that it can be folded on the cushion. When the combination is to be used as a sofa this back is leaned against the wall, or may be held in its place by means of hooks. Two pins, G G, are screwed into the frame A for the purpose of putting on the ends of a strap, H, and to strap the back E when folded on the top cushion. Tubular plates I I, with sliding rods K K, are fastened to the back side of the frame A for the purpose of securing the frame to the sofa-frame, when the frame is overturned for bed purposes, by sliding the rods and passing their ends into corresponding holes made in the sofa-frame. The cross-pieces of the back of the frame E are so arranged that they form in the back part a cavity, which cavity, in combination with a piece of sheeting, L, tacked to the frame, forms a bag to put in pillows, sheets, blankets, straps, and other things. The sofa seat may be arranged with springs or without.

The operation consists in this: The combination being arranged as a sofa, in order to use it as a bed the back E is folded upon the sofa-cushion, the blankets, &c., are taken out of the bag; one end of the strap is put on one of the pins G and the other end on the other pin G, and the strap tightened and buckled; then the frame is turned over, the rods K K secured into the holes, and the bed arranged. This sofa and bed combined may be easily adapted for sleeping-cars and steamboat berths.

What I claim as my invention, and desire to secure by Letters Patent, is—

The revolving frame upholstered as a sofa-cushion on one side and as a bed on the other side, with a folding back as described, the whole constructed and operating substantially in the manner herein described and specified.

H. SCHULTZ.
